JOHANNES WILHELM HOFMANN, OF KOTZSCHENBRODA, NEAR DRESDEN, GERMANY

SUSPENDING DEVICE FOR CONDUCTING CABLES

Application filed December 20, 1929, Serial No. 415,450, and in Germany February 26, 1929.

This invention relates to a suspending device for conducting cables, according to which the fastening of the conducting cable is effected by means of arms jointedly connected with the carrying means of the hanging chain or of the insulator chain, to which arms are jointedly connected the clamping devices or the additional clamps serving as carrying surfaces for the conducting cable in such a manner that the oscillations occurring in the conducting cable cannot pass through the suspending device without hindrance.

To enable this, according to the invention the carrying plates on the carrying means and the clamping device on the carrying plates are pivotally mounted with their respective axes in the middle-line or as near as possible to the middle-line of the cable, so that said axes will come to lie substantially in a horizontal plane through the middle-line of the cable.

Thus it results that the larger undulations pass through the suspending device without hindrance in such a manner that the entire suspending device will pivot around the middle axis, whereas the smaller undulations will effect a swinging of the clamping device or clamping parts around the axes in the carrying plates.

On the drawings the invention is shown by way of example in one mode of construction.

Fig. 1 shows the suspending device in side elevation, and

Fig. 2 is a top plan view, while

Fig. 3 shows on an enlarged scale the clamping device proper or the clamping part with the pivoting point at the carrying flap.

Figs. 4 and 5 show in side elevation and in top plan view, respectively, a modification of the invention.

As will be seen by the drawings, Figs. 1, 2 and 3, *c* are the carrying plates pivotally mounted by means of the pin *e* on the carrying member *h*. On these carrying plates *c* there are arranged in a well known manner the clamping devices or the clamping parts *aa* pivotally secured by means of the bolts or pins *dd*.

According to the invention the middle pin *e* and the two bolts or pins *dd* of the clamp-

ing parts *aa* on the carrying flaps *c* are situated in the middle line or as near as possible to the middle line of the conducting cable *b*, and so will lie in one plane.

Thus the advantage is obtained that the larger oscillations will pass without hindrance through the suspending device in such a manner that the entire suspending device will swing around the axis *e*, whereas the smaller oscillations will effect a swinging of the clamping device or clamping parts *aa* around the axes *dd* in the carrying plates *c*.

For the purpose of enabling the clamping parts *aa* to easily follow the oscillations having short undulations, the clamping parts *aa* are suspended on the carrying plates *c* with their axes *dd* so arranged that each axis *d* is a shorter distance from the inner end *f* of the clamping part than from the outer end *g*, so that the longer lever arm *i* is directed towards the arriving cables, as shown in Fig. 3. The oscillations having short undulations thus cause a movement of the longer lever arm *i* of the clamping parts which corresponds to a smaller movement of the shorter lever arm *k*, whereby the raising and lowering of the portion of cable *b*¹, lying between the clamping parts, is effected to only a small extent.

By an appropriate, for instance curved, formation of the carrying surfaces of the shorter carrying arm *k* of the clamping part the result may be obtained that said shorter carrying arm will make a rolling movement on the portion of the conductor lying between the clamping parts, without any friction on the cable.

For the purpose of enabling an adjustment of the clamping members in relation to the slope of the cable as well as to its oscillations, there may be turnably suspended from the carrying members of the insulating chain a mould-like receptacle for receiving the cable, whereas from said mould there are pivotally suspended the carrying arms, jointly receiving the clamps and being formed in the shape of plates.

As will be seen by Figs. 4 and 5 of the drawings, the carrying plate formed as a mould *n* is pivotally secured to the carrying member *h*.

h of the insulator chain by means of a bolt or pin *e*, the radius *r* of the mould being equal to or larger than the smallest admissible bending radius of the cable used. To the mould

5 *n* there are turnably fixed by means of bolts or pins *mm* the carrying arms *c'c'* formed as plates, whereas to said carrying arms the clamps *a'a'* are hingedly fixed by means of the bolts or pins *d'd'*.

10 The bolt or pin *e* will lie with its axis in the middle of the mould and on a level with the middle of the conductor. The pins or bolts *mm* of the plates *c'c'* will lie adjacent to the bolt or pin *e* and will also have their

15 axes on a level with the middle of the conductor. The clamps *a'a'* are hingedly connected with the mould *n* by means of the carrying arms or plates *c'c'*. The clamps *a'a'* will consequently automatically adjust

20 themselves owing to their turnability around the pins or bolts *d'd'* and owing to the connection of the carrying arms or plates *c'c'* with the mould *n*, from which they extend in the direction of the cable-slope. The clamps

25 *a'a'* serve mainly to clamp the conducting cable, so as to prevent an undesirable sliding thereof due to a one-sided or uneven pull of the cable.

30 The conducting cable *b* will, according to its smaller or larger slope, repose on a smaller or larger part of the mould *n*. The bending radius *r* of the suspension arc reaching from the one side of the suspending device to the other will always remain the same.

35 In Fig. 4 a second position of the conducting cable and the clamping part on a smaller slope is shown in dotted lines.

The larger oscillations of the cable *b* produced by mechanical vibrations will effect a

40 turning motion of the entire suspending device around the axis of the bolt or pin *e*, whereas the smaller oscillations of the cable produced by the higher harmonic oscillations or vibrations will effect a turning motion of the clamping parts *aa* or *a'a'* around

45 the axes of the pins or bolts *dd* or *d'd'* in such a manner that an adjustment of the clamping parts in relation to the slope of the conducting cable as well as swinging move-

50 ments of the conducting cable itself become possible without an undue wear and tear occurring.

55 In connection with high tension conducting cables mainly two kinds of mechanical vibrations will occur, viz: the so-called first harmonic or ground oscillations or vibrations, which have a small frequency and a great amplitude, and the so-called higher harmonic vibrations, which have a great frequency and a small amplitude. The first harmonic oscillations will show great movements of the conducting cable in contrast to the higher harmonic vibrations, which produce very small, practically invisible os-
60 cillations. Both oscillations will take place

in a plane at right angles to the longitudinal axis of the conducting cable. The larger first harmonic oscillations produce a turning movement of the entire suspending device around the pins *e*. They will spread without producing any detrimental effect on the conducting cable. The smaller higher harmonic oscillations, however, would in case no devices for damping these oscillations were provided be reflected from the suspending device and would cause damage to the conducting cable.

70 For the purpose of avoiding these disadvantages there are arranged according to the present invention additional clamps *a'a'* connected to the receiving mould *n* by arms or plates *c'c'*. Said additional clamps *a'a'* can turn within said plates around the pins *d'd'*. They may be of such light weight 75 that they can follow the small oscillations of the higher harmonic vibrations; on the other hand, however, their mass or weight will be large enough so that, by receiving a turning movement from the small oscillations, they will effect a damping of the same. The small oscillations of the higher harmonic vibrations will thus not be able to reach the receiving mould *n* and consequently 80 can not be reflected, whereby a damaging 85 of the cable is avoided.

90 While the explanation just given relates mainly to the mode of action of the device shown in Figs. 4 and 5, it will be appreciated that the same principles apply in the case of the simpler device shown in Figs. 1, 2 and 3, 95 where the cable-supporting and oscillation-damping functions are performed similarly by the parts bearing corresponding reference characters and designations.

100 It will readily be understood that various changes may be resorted to in the form, construction and arrangement of the several parts without departing from the spirit and scope of my invention, and hence I do not intend to be limited to the details herein 105 shown and described except as they may be included in the claims.

110 What I claim is:

1. A suspending device for conducting cables comprising, a carrying member, carrying plates pivoted on the carrying member, and clamping devices pivoted in the carrying plates, the turning axis of the carrying plates in the carrying member and the turning axes of the clamping devices in 115 said carrying plates lying practically in the middle line of the conducting cable.

120 2. A suspending device for conducting cables comprising, a carrying member, carrying plates pivoted on the carrying member, and clamping devices pivoted in the carrying plates, the turning axis of the carrying plates in the carrying member and the turning axes of the clamping devices in said carrying plates lying practically in the mid- 125 130

dle line of the conducting cable, said clamping devices being mounted with their turning axes situated nearer their inner ends.

3. A suspending device for conducting cables comprising, a carrying member, carrying plates pivoted on the carrying member, and clamping devices pivoted in the carrying plates, the turning axis of the carrying plates in the carrying member and the turning axes of the clamping devices in said carrying plates lying practically in the middle line of the conducting cable, said clamping devices being mounted with their turning axes situated nearer their inner ends and the cable-supporting surface of said clamping devices being formed as a convex curve in the portion inward from the point of mounting.

4. A suspending device for conducting cables comprising, a carrying member, a mould pivoted on the carrying member, carrying plates pivoted on the mould, and clamping devices pivoted in the carrying plates, the turning axes of the carrying plates in the mould and the turning axis of said mould in the carrying member lying practically in the middle line of the conducting cable.

In testimony that I claim the foregoing as my invention, I have signed my name this 5th day of December, 1929.

JOHANNES WILHELM HOFMANN.
